CLAIM

(57) We claim the ornamental design for a lid, as shown and described.

DESCRIPTION

FIG. 1 is a top perspective view of a lid according to the new design;

FIG. 2 is a bottom perspective view of the lid shown in FIG. 1;

FIG. 3 is a top plan view of the lid shown in FIG. 1;
FIG. 4 is a cross-section view of the lid shown in FIG. 3 taken through the line 4A-4A;

FIG. 5 is a left side elevation view of the lid shown in FIG. 1;

FIG. 6 is a bottom plan view of the lid shown in FIG. 1;

FIG. 7 is a left end elevation view of the lid shown in FIG. 1;
FIG. 8 is a right side elevation view of the lid shown in FIG. 1;

FIG. 9 is a right end elevation view of the lid shown in FIG. 1. Features shown in broken lines form no part of the claimed design.

1 Claim, 4 Drawing Sheets
